UNITED STATES PATENT OFFICE.

OSCAR B. BJORGE, OF PORTLAND, OREGON, ASSIGNOR TO CLYDE IRON WORKS, OF DULUTH, MINNESOTA, A CORPORATION OF MAINE.

ENGINE FOR LOG YARDING, SKIDDING, ETC.

Application filed August 12, 1925. Serial No. 49,747.

To all whom it may concern:

Be it known that I, OSCAR B. BJORGE, a citizen of the United States, and a resident of Portland, county of Multnomah, and 5 State of Oregon, have invented a new and useful Improvement in Engines for Log Yarding, Skidding, Etc., of which the following is a specification, the principle of the invention being herein explained and 10 the best mode in which I have contemplated applying that principle, so as to distinguish it from other inventions.

The present invention relates to log yarding or skidding engines, and the present 15 construction provides three winding drums, two of them high speed drums and one of them a low speed inhaul drum, all of the drums being so driven that the cables wind on to the drums from their upper sides. 20 The particular feature of importance is the arrangement of the driving mechanism whereby the drums may all be rotated in the same direction and at the desired speeds, this driving mechanism being so arranged 25 as not to interfere with the upper side winding of the cables. To the accomplishment of the foregoing and related ends, said invention, then, consists of the means herein-after fully described and particularly pointed 30 out in the claims.

The annexed drawings and the following description set forth in detail certain mechanism embodying the invention, such disclosed means constituting, however, but one 35 of various mechanical forms in which the principle of the invention may be used.

In said annexed drawings:

Fig. 1 is a top plan view of a yarding engine embodying the present driving mechanism; and Fig. 2 is a side elevational view 40 of the same.

The present yarding or skidding engine consists of a suitable base or frame 1 at one end of which is mounted a source of 45 motor power such as an internal combustion engine 2 having a radiator 3. Ahead of the motor is mounted a driving shaft 5 carried in suitable bearings 6 in the frame and this shaft is driven from the engine 50 shaft 4 by a chain 7 in mesh with the gears 8 and 9 on shafts 4 and 5 respectively. The shaft 5 is thus rotated at relatively high speed and in the same direction as the motor shaft 4. The gears 8 and 9 are 55 mounted on ends of the shafts 4 and 5 which

extend beyond the frame members and the gears and shaft are preferably enclosed in a suitable casing 10. Mounted forwardly of and above the plane of shaft 5 is a second shaft 11 in bearings 12 this shaft carrying 60 the two high speed winding drums, 13 and 14, the drum 13 being the haul back drum and the drum 14 being the straw drum. Mounted on the shaft 5 is a gear 15 in mesh with a large gear 16 on shaft 11 and this 65 large gear 16 is adapted to drive either drum 13 or drum 14 through friction clutches or driving devices 17 and 18.

The end of shaft 5 opposite to gear 9 extends beyond the frame and is provided 70 with a chain gear 19 which is connected by a chain 22 to a gear 20 mounted on the extending end of a shaft 21 mounted ahead of shaft 11 and below the latter. This silent chain is enclosed in a casing 23 and the shaft 21 is thus driven in the same direction as are the shafts 4 and 5. Ahead of the shaft 21 is the second drum shaft 25 carrying the inhaul drum 26 and this inhaul 75 drum 26 is driven through either of a pair of friction devices or clutches 27 and 28, the clutch 27 engaging the drum with a gear 31 in mesh with a driving gear 30 on shaft 21, while the clutch 28 engages the drum with a gear 32 in mesh with a second gear 33 on shaft 21 thus giving the inhaul 80 drum a two speed drive.

It will thus be seen that if the motor runs in a clockwise direction, as illustrated by the arrow on Fig. 2, the driving shafts 5 and 21 will likewise rotate in a clockwise direction but the drums will all rotate in a counter clockwise direction and thus the cables, 35, 36 and 37 on the haulback drum, 90 the straw drum and the inhaul drum, respectively, will all be wound in over the upper surface of the drum as is most desirable. By using a high speed motor, the straw and haulback drums, 14 and 13, are driven at 95 the desired high speed through the chain drive from engine shaft 4 to shaft 5 and the gears 15 and 16. The inhaul drum is driven at slow speed through the chain drive reduction from shaft 5 to shaft 21 and through either pair of gears 30 and 31 or 32 and 33. The driving mechanism is thus compact and the arrangement of the shafts such that the gearing is out of the way so that the cables may be wound in 100 over the upper surfaces of the drums. The 105 110

entire driving mechanism is simple and the outside driving chains are encased against accident. The arrangement of shafts and drums meets the requirements for a slow speed inhaul drum and high speed haul-back and straw drums in a yarding engine which is comparatively inexpensive to manufacture.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a yarding engine, the combination of a base, a motor unit and driving shaft mounted at one end thereof, a pair of spaced driven shafts mounted on said base, driving chain connections between said driving shaft and said driven shafts whereby the latter are rotated in the same direction at different speeds, a second pair of spaced shafts mounted on said base, winding drums on said last-named pair of shafts, and gears on said driven shafts and said drum shafts whereby both of said drum shafts are driven in the same direction.

2. In a yarding engine, the combination of a base, a motor unit and driving shaft mounted at one end thereof, a pair of spaced driven shafts mounted on said base, driving chain connections, between said driving shaft and said driven shafts whereby the latter are rotated in the same direction at different speeds, a second pair of spaced shafts mounted on said base, winding drums loosely mounted on said last-named shafts, gears mounted on said driven shafts and said drum shafts to rotate the latter in the same direction and clutches between said gears on said drum shafts and said drums whereby said drums may be individually connected for rotation.

3. In a yarding engine, the combination of a base, a motor mounted thereon at one end and having a drive shaft extending transversely of said base, a pair of spaced driven shafts mounted transversely of said base, chain and sprocket connections between said drive shaft and one of said driven shafts and between said two driven shafts whereby said shafts are rotated at different speeds

and in the same direction, a pair of winding drum shafts mounted on said base, gear means for driving one of said drum shafts from one of said driven shafts but in the opposite direction, other gear means for driving the second drum shaft from the second driven shaft and in the opposite direction, winding drums on said drum shafts, and means for clutching said drums to said shafts.

4. In a yarding engine, the combination of a base, a motor mounted thereon at one end and having a drive shaft extending transversely of said base, a pair of spaced driven shafts mounted transversely of said base, chain and sprocket connections between said drive shaft and one of said driven shafts and between said two driven shafts whereby said shafts are rotated at different speeds and in the same direction, a pair of winding drum shafts mounted on said base, gear means for driving one of said drum shafts from one of said driven shafts but in the opposite direction, other gear means for driving the second drum shaft from the second driven shaft and in the opposite direction, two winding drums mounted on said first drum shaft and means for clutching either of said drums to said shaft and gear thereon.

5. In a yarding engine, the combination of a base, a motor mounted thereon at one end and having a drive shaft extending transversely of said base, a pair of spaced driven shafts mounted transversely of said base, chain and sprocket connections between said drive shaft and one of said driven shafts and between said two driven shafts whereby said shafts are rotated at different speeds and in the same direction, a pair of winding drum shafts mounted on said base, gear means for driving one of said drum shafts from one of said driven shafts but in the opposite direction, two gears loosely mounted on said second drum shaft, two gears mounted on said second driven shaft and in mesh with said two gears on said second drum shaft, a winding drum mounted on said second drum shaft, and two clutches mounted between said drum and said two gears whereby said drum and shaft may be clutched to either of said two gears to rotate said drum at two different speeds.

Signed by me this 30th day of July, 1925.

OSCAR B. BJORGE.
